CLAIM

The ornamental design for a protective cover for pruning
saw, as shown and described.

DESCRIPTION

FIG. 1 is a front, top perspective view of a protective cover
for pruning saw showing my new design.

FIG. 2 is a front elevational view thereof.

FIG. 3 is a rear elevational view thereof.

FIG. 4 is a left end elevational view thereof.

FIG. 5 is a right end elevational view thereof.

FIG. 6 is a top plan view thereof; and,

FIG. 7 is a bottom plan view thereof.

The length of the claimed design is shown broken away in
the views to indicate indeterminate size, with the under-
standing that the indeterminate length portion not shown in
the drawings forms no part of claimed design.
